UNITED STATES PATENT OFFICE.

JOHN HAYS HAMMOND, JR., OF GLOUCESTER, MASSACHUSETTS.

FLUID CONTAINER.

Application filed March 13, 1916, Serial No. 83,893. Renewed May 16, 1923.

To all whom it may concern:

Be it known that I, JOHN HAYS HAMMOND, Jr., a citizen of the United States, and a resident of the city of Gloucester, 5 county of Essex, and State of Massachusetts, have invented certain new and useful Improvements in Fluid Containers, of which the following is a specification.

Some of the objects of this invention are 10 to provide in a container or receptacle for holding a fluid, or liquid, improved means whereby a perforation or other opening made in a normally imperforate portion of the receptacle or container by a rapidly 15 moving bullet or other projectile, or by other means, may be quickly sealed or covered to prevent the escape of fluid through such perforation or opening; and to provide other improvements as will appear herein- 20 after.

In the accompanying drawings, Fig. 1 is 25 a diagrammatic plan view of a receptacle constructed in accordance with this invention; Fig. 2 is a side elevation of the same; Fig. 3 a section along line 3—3 of Fig. 1; Fig. 4 a section along line 4—4 of Fig. 2; and Fig. 5 a section along line 5—5 of Fig. 1.

Referring to the drawings, one embodiment of this invention comprises a substantially 30 rectangular fluid tight tank or receptacle 10 made of mild steel, copper, or other metal or of any other suitable material, and including a substantially horizontal bottom wall 11, two substantially vertical parallel side walls 12 and 13, two substantially vertical end walls 14 and 15, and a substantially horizontal top wall 16. The lower portions of the end walls 14 and 15 are preferably curved inwardly through an 35 arc of about ninety degrees and are integral with the opposite ends of the bottom wall 11. The top wall 16 is provided with an inlet 17 through which the tank may be filled with a fluid or liquid or other substance or material.

Surrounding and preferably fixedly secured to the bottom wall 11 and side and end walls 12 to 15 of the tank 10, is a layer or covering of material 20, such, for instance, as leather or other material, but preferably such a material as will not form a lip or burr, or which will form only a readily yielding lip or burr when pierced by a bullet or other rapidly moving object.

Surrounding and slidably resting against that portion of the layer or covering 20 of

leather or other material which covers the bottom wall 11 and the end walls 14 and 15, is a strip 25 of sheet material, such, for instance, as oil silk or any other suitable material which is impermeable to fluids. The longitudinal edges 26 and 27 of this strip 25 are parallel to each other and arranged in planes coincident with the outer side surfaces of the portions of the covering 20 60 which are secured to the side walls 12 and 13 of the tank 10. The opposite ends of this strip 25 are wound about two cylindrical horizontal parallel drums 30 and 31 which are rigid and coaxial with spindles 32 and 33 respectively which are rotatably supported in bearings provided therefor in rigid brackets 34 and 35 which are fixedly secured to the walls of the tank 10, whereby the drums 30 and 31 are mounted to rotate 70 about fixed substantially parallel horizontal axis.

Contacting with and covering the outer surface of the strip 25 and holding the strip 25 slidably against the outer surface of the 80 inner layer 20 is an outer layer 36 of material, the longitudinal edges 37 and 37' of which are parallel and flush with the longitudinal edges of the strip 25 and the end edges 38 and 39 which are flush with the 85 upper horizontal surface of the tank. This outer layer 36 may be of the same material as the inner layer 20 or of any other suitable material and is held in place by means of screws 45 extending through projections 90 on the brackets 34 and 35 and by other means as will appear hereinafter.

Slidably contacting against the outer vertical side surfaces of the inner layer 20 respectively, are two horizontally movable 95 strips 50 and 51 of sheet material impermeous to fluid, which may be of the same material as the strip 25 surrounding the end walls. The ends of these side strips 50 and 51 are wound respectively upon two pairs 100 of vertical drums 52, 53, and 54, 55, which are rigid and coaxial with vertical spindles 56, 57, and 58, 59, respectively, the upper ends of which are mounted to rotate in bearings provided therefor in the brackets 34 105 and 35 and the lower ends of which are mounted to rotate in bearings provided therefor in rigid brackets 60 and 61 fixedly secured to the under surface of the outer layer 36 by means of screws 62 and 63 or 110 other fastening means, the vertical drums 52, 53, 54 and 55 being thus mounted to ro-

tate about fixed vertical axes coincident with their longitudinal axes. Contacting with the outer surfaces of the horizontally movable side strips 50 and 51 are two vertical side layers 65 and 66 which may be of the same material as the inner layer or covering 20 of the tank 10. These side layers 65 and 66 are rectangular in shape and secured along their upper edges by screws 10, 67 and 68 to the brackets 34 and 35 and along their lower edges by screws 69 and 70 to the brackets 60 and 61.

Any suitable means may be provided for winding up one of the horizontal drums 30 or 31 and one of each of the pairs of vertical drums 52, 53; and 54, 55, so as to move the corresponding strips of fluid impermeable material, but in the form of this invention illustrated means are provided for 20 moving all of these strips simultaneously, and the means shown for this purpose includes three motion transmitting drums 75, 76 and 77, which are rigidly secured respectively to the spindle 32 of the horizontal 25 drum 30 to the spindle 56 of the vertical drum 52, and to the spindle 58 of the vertical drum 54. Wires or cords 78, 79 and 80 are wound around these motion transmitting drums 75, 76 and 77 respectively, 30 and are passed over pulleys 81, 82 and 83, and are connected at their outer ends to a common ring or securing device 84 to which is connected one end of a wire or cord 85 which passes over a pulley 86 and the other 35 end of which is wound around an actuating drum 87 which is rigidly secured to a spindle 88 which is mounted to rotate about a fixed axis. Rigid and coaxial with the actuating drum 87 is a ratchet 89 which is arranged to be rotated step by step by means 40 of a crank arm 90, one end of which loosely surrounds the spindle 88 and which carries pivotally connected thereto a pawl 91 arranged to engage the ratchet and to 45 rotate it in a clockwise direction, as seen in Fig. 1. A spring pressed pawl 92 engages the ratchet 89 and prevents the actuating drum 87 from unwinding or rotating in a counter-clockwise direction.

50 From the foregoing it is evident that this invention provides means whereby if any of the walls of the tank or receptacle (except the top wall 16) should be pierced as by one or more bullets or other projectiles, 55 the aperture or apertures thus formed could be readily and conveniently sealed simply by rotating the pulley 87 manually or otherwise by actuating the crank arm 90 to a sufficient extent to slide the fluid impermeable strips 25, 50 and 51 to move the aperture or apertures in the strip or strips out of register with the aperture or apertures 60 in the tank and thus close the aperture or apertures in the tank.

65 Although only a single form has been

shown in which this invention may be embodied, it is to be understood that the invention might be applied in various forms without departing from the spirit of the invention or the scope of the appended claims.

Having thus fully described my invention, I claim:

1. The combination with a container for fluid, comprising a bottom wall, and two pairs of walls extending upwardly therefrom, of a strip of sheet material impervious to fluid surrounding said bottom wall and one of said pairs of said upwardly extending walls, said strip being movable with respect to said container, to close any aperture that might be formed in given normally imperforate portions of said bottom wall and said two of said upwardly extending walls, and a pair of strips of said material extending upon opposite sides of said container and movable with respect thereto to close any aperture that may be formed in the other of said pairs of said upwardly extending walls.

2. The combination with a container for fluid, comprising a bottom wall, and two pairs of walls extending upwardly therefrom, of a strip of sheet material impervious to fluid surrounding said bottom wall and one of said pairs of said upwardly extending walls, said strip being movable with respect to said container, to close any aperture that might be formed in given normally imperforate portions of said bottom wall and said two of said upwardly extending walls, and a pair of strips of said material extending upon opposite sides of said container and movable with respect thereto to close any aperture that may be formed in the other of said pairs of said upwardly extending walls, and means operative to move said strips simultaneously with respect to said container.

3. The combination with a container, of a plurality of strips of material substantially impervious to fluid, and means operative to move a plurality of said strips simultaneously with respect to said container in predetermined paths, whereby any aperture that may be made in certain normally imperforate portions of said container is closed.

4. The combination with a container for a fluid, of a plurality of strips of material substantially impervious to fluid and means operative to move a plurality of said strips simultaneously with respect to said container in predetermined paths whereby any aperture that may be made in certain normally imperforate portions of said container is closed.

5. The combination with a container for a fluid, of a plurality of strips of material substantially impervious to fluid, one of

5 said strips having substantially parallel edges and being movable with respect to said container in the direction of said edges, and two of said strips being arranged upon opposite sides of said first mentioned strip and movable in parallel planes substantially perpendicular to said first mentioned strip.

6. The combination with a container for a fluid, of a plurality of strips of material 10 impervious to fluid arranged to be moved with respect to said container to close any aperture that may be made in certain normally imperforate portions of said container, one of said strips having portions 15 thereof movable in substantial parallelism while another portion of said strips is moving at a right angle to the other mentioned portions, and two of said strips being disposed to move in substantial parallelism in 20 planes approximately coincident with the edges of the first mentioned strip.

7. In a fluid container, the combination with a plurality of sheets in parallel with each other for retaining the liquid within 25 the container, of means for moving at least one of said sheets in the plane of the sheet.

8. The combination with a vessel having a pair of walls in spaced parallel relation and a third wall interconnecting said first 30 named walls, of a strip of sheet material

impermeable to the flow of fluid into and out of said vessel, and positioned adjacent said walls, said strip being movable with respect to said vessel to close any aperture that might be formed in given normally imperforate portions of said walls.

9. The combination with a vessel having two pairs of walls, the walls of each pair being in spaced parallel relation with respect to each other, and a fifth wall joining 40 said walls, of a strip of sheet material impermeable to the flow of fluid into and out of said vessel and surrounding one of said pairs of said last named walls, said strip being movable with respect to said vessel to 45 close any aperture that might be formed in given normally imperforate portions of the walls surrounded by said strip, and a pair of strips of said material extending upon the opposite sides of said vessel, and 50 movable with respect thereto to close any aperture that might be formed in the other of said pairs of walls.

Signed at New York, in the county of New York and State of New York, this 10th 55 day of March A. D. 1916.
